Patented June 19, 1917.

UNITED STATES PATENT OFFICE.

ELMER T. GALLEY, OF HUNTINGTON PARK, CALIFORNIA.

PLASTER-BOARD.

1,230,400.

Specification of Letters Patent. Patented June 19, 1917.

Application filed January 31, 1914. Serial No. 816,130.

To all whom it may concern:

Be it known that I, ELMER T. GALLEY, a citizen of the United States, residing at Huntington Park, in the county of Los Angeles and State of California, have invented a new and useful Plaster-Board, of which the following is a specification.

This invention relates to the manufacture of boards that are applicable in the construction of buildings to form parts of the walls and ceilings thereof, that are capable of directly forming the exterior surfaces of walls and that are more particularly designed to be covered with plaster for forming the impervious wall faces either inside or outside the building.

An object of the invention is to produce a light, strong and cheap substitute for wood and metal lathing and to provide a board forming a substitute of this character which will be impervious to moisture and which will form a good insulator in addition to forming a more or less fire-proof board upon which plaster may be applied and which is so constructed that the plaster will clench therein with superior bond and with a saving of plaster as compared with usual forms of open lathing of wood or metal.

An object is to provide a plaster board which can be readily fastened to metal building structures in a practically fire-proof manner.

Further objects and advantages may appear from the subjoined detail description.

The invention may be understood by reference to the accompanying drawings.

Figure 1 is a perspective fragmental view of a plaster board constructed in accordance with this invention.

Fig. 2 is a section on line x^2 , Figs. 1 and 4.

Fig. 3 is a perspective fragmental view of a plaster board showing a back plate specially equipped for the ceiling.

Fig. 4 is a section on line x^4 , Figs. 1 and 2.

Fig. 5 is a fragmental view of a plaster board constructed without reinforcements.

Fig. 6 is a fragmental perspective view of a mold for forming a plaster board.

Fig. 7 is a section of a fragment of the mold with a plaster board formed therein. The section is on line indicated at x^2 , Figs. 1 and 4.

Fig. 8 is a section of a plaster board secured by nails to joists, said plaster board having plaster secured thereto.

This novel plaster board comprises a

cementitious base or body 1 and two face plates 2 and 3, one of said face plates 2 constituting a perforated form sheet having depressions, said sheet being slotted and indented, the other face plate, or more properly back plate 3, being smooth and flat, and the cementitious base or body conforming to and adhering to the inner sides of the face plates 2 and 3 and having depressions extending to bottoms within the base, said depressions registering with said perforations. Alternate intermediate portions between the parallel slits in the face plate 2 are indented forming open-sided indentations with tongues 4, integral with the form sheet and which recede from the outer side of the face plate 2 and project from the inner side of said face plate, said indentations forming inserts in the body 1. The indentations or inserts at 4 owing to the provision of the slits have free longitudinal edges spaced apart from the edges of the intermediate portions so that plaster can enter sidewise through the slits and come into contact with exposed portions of the cement body 1 so as to strongly adhere thereto. The face plate 2 of the plaster board with its indentations forms a clenching surface to which plaster when applied will readily adhere, while the face plate 3, being smooth and flat, forms a neat finish for the other side of the plaster board.

A board thus constructed is light, strong, rigid and impervious and can be fastened in place, for instance, by nails a , Fig. 8, driven through the plaster board into a support b adapted to receive the same. In finishing a wall or ceiling of a building, plaster may be applied in the usual manner of plastering and the same will enter the indentations 4 and pass through the slits into the sides of undercut, dovetail mortises or wedge-shaped cavities 5 in which the indentations are accommodated, said mortises being expanded at their bottoms and contracted at their inlets, so that the clenchers of plaster will be positively retained thereby. Thus it is seen that the portions of the body 1 between adjacent cavities 5 form dovetail or wedge-shaped keys.

The face and back plates 2, 3, may be made of any suitable material to which the body may be applied. I have successfully used tarred paper for the plates and cement plaster for the body and I contemplate in some instances the use of asbestos paper or any fireproof material for the plates, and

any plastic that hardens may be used to form the body. It is preferable in the economy of manufacture that quick setting cement be used for the body.

5 A valuable feature of this invention is dependent upon slitting the face plate and indenting the portion between the parallel slits, for thereby the cement or plaster body of the plaster board is exposed at said slits and indentation, and when the plaster board is in place as in ceiling work and a coating 10 of wet plaster is applied, such wet plaster will adhere to the exposed plaster or cement of the plaster board with greater suction and with less possibility of slipping out of the 15 indentations than would be the case if said wet plaster did not come in direct contact with such cement body. Furthermore all danger of slippage from softening of the 20 paper is avoided at these particular exposed portions, thus holding the wet plaster coating firmly until it is dried.

Furthermore I am not aware that there 25 has yet been provided a construction of plaster board in which dove-tail recesses or depressions have been provided or suggested for the purpose of holding the plaster coating subsequently to be applied.

It is also desirable for fire and earthquake-proof buildings that the board be appropriately reinforced and with this object in view and a further object of providing fastening means which can be applied to the supporting structure to hold the board in 35 place without making perforations therein, this reinforcement may readily be applied in a practical way by placing wires in the place to be filled with the plaster or cement body. Plaster boards made of certain compositions 40 of cement would crack if a nail were attempted to be driven through them, due to the unyielding character of such cement. When made of such compositions of cement, the plaster boards are provided with fastening 45 means that are formed embedded in the cement whereby the danger of cracking is removed. Said fastening means may also be applied with any character of cement.

In Figs. 1 and 2 galvanized iron or steel 50 wires 6, 7 and 8 are shown arranged criss-cross in the body 1, the wires 6 being threaded through the slitted and indented sheet and passing through the slits between pairs of wires 7 and pairs of loops 9 of said face 55 plate; the wires 8 extending transversely of the wires 6 and 7. The wires 6 hold the indented portions 4 against the bottoms of the mortises 5, thus maximizing the bonding effect between the body and the face plate. 60 In Fig. 1 all the wires are shown as having their terminals projecting beyond the edges of the board.

The embodiment shown in Fig. 3 finds special utility when the plaster boards are 65 used for a ceiling. The terminals of certain

of the wires in this embodiment are shown as projecting from the back plate of the plaster board so as to be in position to be fastened to the ceiling joists whereby the plaster boards are properly secured in position.

The terminals may be variously constructed, in some instances, extending freely to be wound or twisted around parts of the securing structure, as the terminals of the wires 6 and 8 projecting from the edge of the plaster board and the terminals of the wires 7' projecting from the back plate of the plaster board as shown in Fig. 3, and in other cases being formed into eyes, as the eyes 10 of the wires 7 in Fig. 1.

70 The method of constructing the plaster board is as follows:

First, the face plate 2 is provided with the slits and indentations. In the case of tarred paper the slits and indentations are formed 85 at one operation while such paper is in a softened condition, such condition being effected by heating the forming instruments. Preferably the indentations may be made by passing the paper between heated rolls of 90 suitable conformation to produce the slits and indentations. Said indentations are preferably semi-cylindric or curved segments thus giving an arched form to the 95 plaster that will lodge therein.

The arched form of the plate thus formed increases the strength of the completed board as compared with a board made with only flat face plates; and when it is desired to use the reinforcing wires such wires may 100 be threaded through the loops formed by the indentations.

When the sheet or plate has thus been slitted and indented it is then laid on the bottom of the mold 12 which is provided 105 with cylindric projections 13 that are preferably provided at their crowns with notches 14 to receive the wires 6 that have been threaded through the slits.

The projections 13 are arranged in pairs 110 each having one smooth side 11 which is opposite to and faces the smooth side of its companion projection and each having an outer inclined receding side 15 which is parallel to the smooth sides; the smooth sides 115 being adapted to accommodate the projection 16 of a wedge 17, and the inclined receding sides 15 being provided to form the undercut portions 5 in the indentations 4.

The sides 18 of said mold are provided 120 with vertical slits 19 and 20, the openings or perforations formed by the slits 19 being aligned with the notches 14 so that wires 6 will rest in the notches and have their terminals resting in the slits 19, the openings 125 or perforations formed by the slits 20 being located intermediate those formed by the slits 19 to accommodate the terminals of the wires 7. Preferably the wires 8 are laid under and transverse to the wires 6 and 7 130

between the rows of projections 13, and the terminals of said wires may be accommodated in the openings or perforations formed by slits 21 provided in the ends 22 of said 5 mold, the slits 21 being cut deeper than the slits 20 for the purpose just described.

When the face plate and the wires are thus arranged a plastic cement body, which may be of any suitable material that will 10 adhere to the face plate and will harden, is poured into the mold in measured quantity just sufficient to fill the mold, whereupon the back face plate 3 is placed on top of the plastic body before the same has set and the 15 pressure plate 23 is then forced down by any suitable means, not shown, to solidly compress the back plate 3 onto the plastic body and to compress such body against the face plate 2, thus forcing the plastic mass to 20 form to and adhere to the face plate and the wires. The pressure is then removed and the plaster board having become set is removed and stored for seasoning.

The tongues 4 are integral with the form 25 sheet or face plate 2 and attached thereto at one side of the perforations formed at the depressions between the slits, and lying along the bottoms of the body depressions in the cementitious base so as to cover the 30 bottoms of the depressions and leave the cementitious material of the body exposed on the sides of the depressions. By forming the tongues 4 of strips between slits and extending the tongues the full length of their 35 respective depressions and having them connected to the sheet 2 at both sides of the perforations, strength of the finished board is conserved.

When the modification shown in Fig. 3 is 40 being molded, before putting the back plate 3 in place and applying pressure, terminals of certain of the wires, as for instance the wire 7', are extended up from the mold. Then in the same manner just described 45 with the other modification, the back plate 3 is placed on top of the plastic body, it having openings 24 provided to accommodate the upwardly extending terminals of the wire 7'; and then the pressure plate 23 50 forced down upon said back plate 3.

Preferably the plaster board is provided around its margins with a border 25 that is flat.

In order to insure a tight and strong joint 55 between the several boards when fastened to the structure, the boards may be provided with a tongue-and-groove arrangement, the tongue 26 on one edge complementing the groove 27 in the opposite edge, said tongue 60 and groove being of any desired form.

It is particularly noted that the wedge-shaped cavities 5 securely hold the plaster in place even when said plaster is wet and consequently very heavy and more or less plastic, and that the secure keying of the plaster

is effected by reason of the plaster spreading out behind the face plate 2 much the same as it does behind the ordinary spaced-apart lath, but at the same time the indentations 4 hold the plaster that is forced back of said face plate so that waste of the plaster cannot occur as with the ordinary lath and yet keying of the plaster in place is as secure or more secure than when ordinary lath are employed.

When ordinary lath are used the plaster becomes keyed in place by reason of its being forced through the interstices and hooking over the backs of the lath, and when so-called expanded metal lath are employed 75 80 the waste of plaster becomes excessive for the sharp edges of the metal sever the plaster and cause a great portion of the plaster that should hook over the backs of the lath to fall down between the walls and become useless.

It is obvious that various changes and modifications to the details of construction may be made without departing from the spirit of the invention.

I claim:—

1. A plaster board comprising a cement body having a surface provided with dovetail mortises, and a face plate upon said surface provided with slits opening through said face plate to the dovetail mortises.

2. A plaster board comprising a back plate, a face plate having slits spaced in pairs, the portion of the plate between the adjacent slits of each pair being indented, and a body between and adhering to said plates.

3. A plaster board comprising a body having a surface provided with mortises, a face plate on said surface having slits spaced in pairs, the portion of the plate between the adjacent slits of each pair being indented, and wires extending through said body and through the slits from mortise to mortise, said wires holding the indented portions against the bottoms of the mortises.

4. A plaster board comprising a body having a surface provided with dovetailed mortises, said mortises being expanded at their bottoms and contracted at their inlets, and a face plate provided with slits adjacent the sides of said mortises, the intermediate portion of said face plate being indented into said mortises so that plaster can enter sideways through the slits and come into contact with the exposed side portions of the body so as to strongly adhere thereto.

5. A plaster board comprising a body having a surface provided with mortises, a face plate on said surface having slits spaced in pairs, the portion of the plate between the adjacent slits of each pair being indented, a back plate on said body provided with openings, and wires extending through said body and through the slits from mortise to mortise, said wires holding the indented por-

tions against the bottoms of the mortises and one end of each wire projecting from an edge of the plate and the other end of each wire being bent at right angles to the body 5 part of the wire and projecting through the openings of the back plate.

6. A plaster board comprising a face plate provided with slits opening therethrough and spaced in pairs, the portion of the plate 10 between the adjacent slits of each pair being indented to form loops projecting from one side of said plate, a back plate, and a body between said face plate and back plate extending between the back and front plates 15 and to the edges of said loops.

7. A plaster board comprising a face plate provided with slits opening therethrough and spaced in pairs, the portion of the plate 20 between the adjacent slits of each pair being indented to form loops projecting from one side of said plate, a back plate, and a body between said face plate and back plate extending from plate to plate and to the edges of said loops between the pairs of slits 25 and undercut at said edges.

8. A plaster board comprising a body having spaced apart dovetail keys, and a face plate indented into the spaces between the keys, said face plate being provided with 30 slits in pairs extending along two edges of each of said indentations to expose the sides of said keys.

9. A plaster board comprising a body having a surface provided with dovetail mortises, and a face plate indented into said mortises and provided with slits extending along two edges of each indentation to expose the side walls of said mortises. 35

10. A plaster board comprising a face 40 plate, a back plate, a body between said face plate and back plate, wires extending inside the body between said plates, terminals of some of said wires projecting from the edges of said plate and terminals of other of said 45 wires projecting from the face of the back plate, said edge terminals being formed into eyes to afford fastening means to one another and the face terminals affording means to fasten to the ceiling rafters when the 50 plaster boards are used for a ceiling.

11. A plaster board comprising a body, and a face plate, said face plate being slitted and indented at alternate intermediate portions between the slits to form inserts having 55 free longitudinal edges spaced apart from the edges of the intermediate portions.

12. A plaster board comprising a cement body having a surface provided with dove-

tail mortises, and a face plate upon said surface provided with perforations through 60 said face plate to the dovetail mortises.

13. A plaster board comprising a body having a surface provided with dovetail mortises, said mortises being expanded at their bottoms and contracted at their inlets, and a face plate provided with openings adjacent the sides of said mortises, the intermediate portion of said face plate being indented into said mortises so that plaster can enter sidewise through the openings and 70 come into contact with the exposed side portions of the body so as to strongly adhere thereto.

14. A plaster board comprising a body having spaced apart dovetail keys, and a 75 face plate indented into the spaces between the keys, said face plate being provided with narrow openings in pairs extending along two edges of each of said indentations to expose the sides of said keys. 80

15. A plaster board comprising a body, and a face plate, said face plate being perforated and indented at alternate intermediate portions between the perforations to form inserts having free longitudinal edges 85 spaced apart from the edges of the intermediate portions. 90

16. A plaster lath, embodying a cementitious base and a form sheet therefor, said form sheet being perforated and the cementitious base having depressions extending to bottoms within the base, said depressions registering with said perforations, and on the side of which depressions the cementitious material of the base is exposed. 95

17. A plaster lath, embodying a cementitious base and a form sheet therefor, said form sheet being perforated and the cementitious base having depressions extending to bottoms within the base, said depressions 100 registering with said perforation, and tongues integral with the form sheet attached thereto at one end at one side of the perforations and lying along the bottoms of the body depressions so as to cover the bottoms of the depressions and leave the cementitious material of the body exposed on the sides of the depressions. 105

In testimony whereof, I have hereunto set my hand at Los Angeles, California, this 110 26th day of January, 1914.

ELMER T. GALLEY.
